UNITED STATES PATENT OFFICE.

JAMES BIRNEY BURRELL, OF WRIGHTS, CALIFORNIA.

MACHINE FOR CUTTING BOARDS.

SPECIFICATION forming part of Letters Patent No. 439,321, dated October 28, 1890.

Application filed November 27, 1889. Serial No. 331,783. (No model.)

To all whom it may concern:

Be it known that I, JAMES BIRNEY BURRELL, a citizen of the United States, residing at Wrights, in the county of Santa Clara and State of California, have invented an Improvement in Machines for Cutting Boards; and I hereby declare the following to be a full, clear, and exact description thereof.

My invention relates, generally, to the class of wood-working machinery, and especially to that class which is designed for cutting wood into slabs or boards, and more particularly for cutting boards from logs.

My invention consists in the peculiar constructions, combinations, and arrangement hereinafter fully described, and specifically pointed out in the claims.

The object of my invention is to provide an effective and durable machine adapted for cutting boards from logs.

Referring to the accompanying drawings, Figure 1 is a side elevation of my machine. Fig. 2 is a top view of the same. Fig. 3 is an end view. Fig. 4 is a bottom view of the 25 knife or bit.

A is a fixed guide-rail consisting of an oblong plate having oppositely-beveled top and bottom edges, (shown at *a*), and a central longitudinal strength-rib *a'*. To this guide-rail are secured the two fixed bearing-blocks B, having on their lower ends the piercing-points *b*. Through one side of the blocks pass the holding-screws or screw-bolts *b'*, the tops of which are provided with wrench-holds, as shown, whereby the ends of the screw-bolts may be projected below the blocks in order to fix them to the log, as will be presently described. In the upper portion of these blocks are freely pivoted the swinging tubular-holders C, in which are inserted adjustably the shanks *d* of the dogs D, said shanks being held in position by the set-screws *c*, which enable the dogs to be set in or out for the purpose of accurately placing and holding the 45 guide-rail in a perpendicular position. Upon the beveled top and bottom edges of the guide-rail A is mounted by corresponding bevels (shown in Fig. 3) the sliding carrier E. The outer face of this carrier has a vertical bevel-sided groove or seat *e* made in it, in which the bit-plate F is fitted, as shown in Fig. 2. The lower end of this bit-plate is provided or

has connected with it the bit or knife G. This is a double-ended one, having planing-points at each end, and at its middle the scoring-cutting-edges *g* for cutting the sides of the shaving, said scoring-edges being carried down below the horizontal plane of the points, so that they will score the wood on the previous movement of the knife or bit before its 60 planing-points cut the shaving out. At the top of the bit-plate is formed or secured a nut H, in which is seated the vertical screw I, the lower end of which is properly stepped, as shown at *i* in the sliding carrier. The lower 65 end of the screw is provided with a ratchet-wheel or disk J, the teeth of which engage with a fixed rack K, one at each end, the body of which is secured to the fixed guide-rail A, as shown in Fig. 1. Any suitable means may 70 be employed to move the carrier back and forth along the fixed guide-rail, and for this purpose I have shown a cord or rope L attached to each side of the carriage.

The operation of the device is as follows: 75 It is intended to be mounted upon a log, which I have shown in dotted lines in Figs. 1 and 3. It is held firmly to the log by turning down the screw-bolts *b'* of the bearing-blocks B so that their points will enter the log; but it is 80 temporarily held in position before and while these bolts are being screwed down by the holding-points *b* of the blocks, which penetrate the wood from the weight of the machine. The whole device is further and securely held to the log by the dogs, which, on account of their adjustment, are adapted to throw the guide-rail into a perfectly perpendicular position. When everything is ready, the carrier is drawn back and forth on the 85 guide-rail. On the trip over, the scoring-edges of the bit cut on each side, while on the trip back the planing-point cuts out the shaving, while the scoring-edges cut deeper for the next shaving. On the forward trip again 90 the other point cuts out the shaving, while the scoring-edges cut deeper into the sides again. Now at each trip of the carriage the bit is fed down to its work. This is effected by the ratchet-wheel of the screw coming in 95 contact with the fixed racks at the ends of the machine.

As shown in the drawings, the operation is this: On the movement to the left the planer-

- bit is down to its work, and as the ratchet of the screw passes the fixed rack at that end it slips the teeth of said rack, which does not, therefore, affect the feed of the bit. As it passes 5 the rack at the other end, it again slips the teeth; but as it returns, and just before the bit reaches the log, the ratchet-wheel of the screw comes in contact with and is turned by the rack at the left-hand end, so that the 10 screw is turned, and thereby, through the fixed nut above, the bit is fed down. At the first end, just after it leaves the log, the ratchet-wheel again comes in contact with the rack at the right-hand side and engaging its 15 teeth the bit is again fed down, so as to be ready for the forward trip. Thus on each trip the bit is fed down to its work and in time will cut through the log or through such portion of it as may be necessary.
- 20 The device can be placed in a horizontal position as well as a vertical position, so as to cut into the log from the side, when desired, after it has cut down perpendicularly the required number of boards.
- 25 I am aware of the employment in some planes of bits having a planer-point and scoring-edges, and I am also aware of machines for making that article of manufacture known as "excelsior," and in which a bit is reciprocated over the block and the block itself continually fed up to the bit. I do not therefore claim, broadly, the cutting into wood by the reciprocating movement of a bit or knife; but
- 30 35 What I do claim as new, and desire to secure by Letters Patent, is—
1. In a machine for cutting boards, the fixed guide-rail, the carrier mounted and adapted to slide thereon, and the bit or knife 40 mounted on the carrier, in combination with the bearing-blocks B, secured to the fixed guide-rail and engaging the log, whereby the rail is primarily held to said log, and the screw-bolts b', passing through said blocks 45 and having their points adapted to penetrate the log, substantially as described.
  2. In a machine for cutting boards, the fixed guide-rail, the carrier mounted and adapted to slide thereon, and the bit or knife 50 of the carrier, in combination with the fixed blocks B, secured to the rail, the penetrating points b of said blocks for holding the rail primarily to the log, and the screw-bolts b', seated in said blocks, the points of which are 55 adapted to penetrate the log, substantially as described.

3. In a machine for cutting boards, the fixed guide-rail, the carrier mounted and adapted to slide thereon, and the knife or bit of the carrier, in combination with the fixed 60 blocks B, secured to the guide-rail, and the dogs D, hinged to the blocks for holding the machine to the log, substantially as described.

4. In a machine for cutting boards, the guide-rail, the sliding carrier, and the bit or 65 knife of the carrier, in combination with the blocks B, secured to the guide-rail, the tubular holders hinged to the blocks, the dogs fitted adjustably in said holders, and the set-screws for holding the dogs where adjusted, 70 substantially as described.

5. In a machine for cutting boards, the fixed guide-rail, the sliding carrier thereon, and the bit or knife of the carrier, in combination with the blocks B, secured to the 75 guide-rail and having the piercing-points b, the screw-bolts b', seated in the blocks and having their lower ends adapted to penetrate the log, and the adjustable dogs D, hinged to the blocks, substantially as described. 80

6. A machine for cutting logs, consisting of the combination of the guide-rail, the bearing-blocks B, secured thereto and having the screw-bolts b', and the adjustable dogs D, whereby the rail is fixed to the log and adjusted to a perpendicular position, the carrier mounted on the rail and adapted to slide thereon, the vertically-movable plate seated in the face of the carrier, the bit or knife at the lower end of the plate, and the means for 90 feeding the bit or knife, consisting of the nut on the top of the plate, the screw seated in the nut, the ratchet-wheel on the screw, and the racks on ends of the guide-plate for engaging the ratchet-wheel, substantially as de- 95 scribed.

7. In a machine for cutting logs, the double-ended reciprocating knife or bit having planing-points at each end, and intermediate scoring-edges, said edges being extended below the horizontal plane of the points, so that they will score the wood on the previous movement of the knife before the planing-points cut the shaving out, substantially as de- 100 scribed. 105

In witness whereof I have hereunto set my hand.

JAMES BIRNEY BURRELL.
